UNITED STATES PATENT OFFICE.

ENOS THOMPSON, OF RADNOR, WEST VIRGINIA.

LIFE-SAVING SECTIONAL STEAMER.

1,151,420.

Specification of Letters Patent. Patented Aug. 24, 1915.

Application filed April 3, 1915. Serial No. 19,000.

To all whom it may concern:

Be it known that I, ENOS THOMPSON, a citizen of the United States, residing at Radnor, in the county of Wayne and State 5 of West Virginia, have invented certain new and useful Improvements in Life-Saving Sectional Steamers, of which the following is a specification, reference being had therein to the accompanying drawing.

10 This invention relates to a life-saving sectional steamer and has for its principal object the production of a detachably carried life-saving steamer which is adapted to move from the disabled ship or boat which 15 supports the same as the ship sinks, whereby the life-saving steamer may move safely away without the loss of life usually incurred by the sinking of ships.

Another object of this invention is the 20 production of a life-saving steamer or boat which is detachably carried upon the upper deck of the main ship, whereby, when the main ship sinks the life-saving steamer may move down a trackway so as to be directed 25 upon the surface of the water, so as to float independently of the main ship.

Another object of this invention is the 30 production of a simple and efficient supporting means for the life-saving steamer, this means being so formed as to normally support the life-saving steamer in such a manner as to allow the same to be released and moved from the upper deck of the main ship when necessary.

35 With these and other objects in view, this invention consists of certain novel combinations, constructions, and arrangements of parts as will be hereinafter fully described and claimed.

40 In the accompanying drawings:—Figure 1 is a side elevation of the invention, showing the same carried upon the upper deck of a ship. Fig. 2 is a fragmentary top plan view of the upper deck of a ship, showing 45 the supporting elements and guide elements used in carrying the life steamer. Fig. 3 is a transverse section through the life steamer, showing the same carried upon the upper deck of the ship. Fig. 4 is a fragmentary 50 sectional view through the auxiliary steamer or life ship, showing the same mounted in position upon the upper deck of a ship. Fig. 5 is a transverse fragmentary sectional view of the supporting elements for the life 55 ship. Fig. 6 is a transverse sectional view of one of the supporting brackets, showing

the rollers carried thereby. Fig. 7 is a fragmentary sectional view of one end of one of the supporting brackets.

Referring to the accompanying drawings 60 by numerals 1 designates the upper deck of the ship 2. This ship 2 is adapted to be constructed in accordance with the general plan of ships now in use and is adapted to carry the life ship adjacent its stern. The 65 life ship 3 has inwardly extending portions 4 formed at a spaced distance above the bottom portion 5 thereof. In this manner an open space 6 is provided within which the rails 7 are supported by means of the screws 70 or other securing members 8. The rails 7 are carried adjacent the side portions of the life steamer or boat 3 and extend longitudinally throughout its entire length, as shown in Fig. 4.

75 Brackets 9 are positioned upon the upper deck 1 of the ship 2 as clearly shown in Figs. 2 and 3 so as to be secured in parallel spaced relation. These brackets 9 are substantially U-shaped in cross section and have 80 the stub axles 10 extending therethrough so as to be supported by the sides of the brackets. Upon each stub axle 10 there is carried a roller 11 having an enlarged flange 12 formed upon one side thereof. The 85 screws or other securing members 13 pass through the lower portions of the brackets 9, as shown in Fig. 2, for fixedly retaining the brackets in their correct positions upon the deck 1. The life steamer or boat 3 is 90 adapted to be normally carried upon the upper deck 1 of the ship 2 so as to allow the rails 7 to rest upon the rollers 11.

95 It will be noted by referring particularly to Fig. 4 that the rollers adjacent the forward end of the brackets 9 are journaled in a higher plane than the rollers at the rear end of the brackets 9, thereby forming an inclined plane which will cause the rear end of the life ship or boat 3 to be tilted so that 100 upon being released, it will automatically ride upon the rollers 11 so as to move from the upper deck of the ship 2. A plurality of integral parallel ears 14 extend from the side portions of the brackets 9 for the purpose of carrying the vertical shafts 15 upon which the bearing rollers 16 are rotatably mounted. These ears 14 extend from the inner sides of the brackets 9 so as to allow 105 the bearing rollers 16 to engage the outer side surfaces of the connecting supports 17 which connect the floor 5 with the inwardly 110

extending portions 4 of the life steamer 3. By this construction it will be seen that as the life steamer or boat 3 moves toward the stern of the ship 2, the bearing rollers 16 will hold this steamer 3 against lateral or side movement and therefore will prevent the life steamer from accidentally falling or moving over the side portions of the ship 2. It is of course obvious however, that the bearing rollers 16 will allow the life steamer 3 to easily move thereover as the same is being removed from the upper deck 1 of the ship 2.

An L-shaped guard 19 is carried adjacent the outer side portions of each bracket 9 and these guards are secured by means of the screws 20. It will be seen that the upper end of the guards 19 engage the outer side surfaces of the life steamer 3 at a distance above the open portions 6. In this manner, any foreign object is prevented from accidentally lodging under the open portions 6 and preventing the efficient operation of the bearing rollers 16 or the supporting rollers 11. In this manner the supporting members will always be retained in an operative position without danger of interference from foreign objects.

When the life ship is in its normal position upon the upper deck of the ship 2, it will be retained against accidental displacement by any suitable coupling, such for instance as the overlapping bars herein disclosed at 21, through which the retaining pins 22 may be detachably passed for coupling the life steamer or boat upon the upper portion 1 of the ship 2. This life steamer is adapted to be provided with all the conveniences of the main ship. Therefore, there is provided the engine room 23 for the purpose of inclosing any suitable engine to which the motor power can be supplied. This engine of the life steamer is adapted to furnish power for generating the electricity used for illuminating the main ship. Therefore, when the main ship is sinking, although the engine room and the engine thereof may be flooded, the engine in the life steamer will be running and therefore the lights on the main ship will not go out. This life steamer is also adapted to be provided with a wireless 24, by means of which assistance may be summoned when necessary.

When the ship or vessel 2 strikes some foreign obstacle, such for instance as an iceberg, and begins to sink or is caused to sink or is disabled by any other means, the passengers and crew may assemble within the life steamer 3. The pins 22 which are carried upon each side of the life steamer 3 may be removed so as to free the bars 21 from engagement with each other. This operation takes place at the time the sea reaches the level of the upper deck 1.

Owing to the fact that the rollers 11 are carried at inclined planes within the brackets 9, the life steamer 3, as herein set forth, is carried at an angle so as to ride gently over the upper deck 1 of the vessel 2 over the rollers 11 and between the bearing or guiding rollers 16, so as to rest upon the surface of the sea. The motor power for the life ship will of course be furnished by the engine thereof whereby the life steamer may readily and quickly be driven from the immediate vicinity of the main vessel or ship 2 whereby upon the complete sinking of the main vessel the vortex thereof will not draw the life steamer 3 down therewith.

From the foregoing description it will be seen that a very simple and efficient life steamer has been produced which is normally carried upon the upper deck of the main steamer or ship but which may be released, upon the sinking of the main ship, whereby the life steamer will be efficiently guided from the main ship over the stern thereof by means of the simple and efficient supporting and guiding elements used in connection therewith.

What I claim is:—

1. In a device of the class described the combination of a ship, a life steamer carried upon the upper portions of said ship, said life steamer provided with inwardly extending portions adjacent its lower portions, said inwardly extending portions being formed at a spaced distance above the bottom of said life steamer, L-shaped guards fixedly carried upon the upper portions of said ship in parallel spaced relation, said guards extending upwardly so as to inclose the open portions of said life steamer, and means carried upon the upper portion of said ship and within the open portions of said life steamer for supporting the life steamer in a detachable position, said means being adapted to allow the life steamer to move upon the upper portions of said ship, said guards being adapted to protect said means for preventing the same from becoming inoperative by the lodging of foreign objects within said open portions.

2. In a device of the class described, the combination of a ship having an upper deck, a life steamer positioned upon the upper portion of said ship, longitudinal brackets fixedly carried upon said upper deck, supporting rollers carried by said longitudinal brackets, supporting rails fixedly carried upon the lower portions of said life steamer and normally bearing upon said supporting rollers, said rollers being carried in a slanting plane so as to hold said life steamer in a tilted position, and means for normally retaining the life steamer against accidental displacement, said means being adapted to be released upon the sink-

ing of the ship, whereby the life steamer will ride over said supporting rollers and into the sea.

3. In a device of the class described, the combination of a ship having an upper deck, a life steamer positioned upon the upper portion of said ship, longitudinal brackets fixedly carried upon said upper deck, supporting rollers carried by said longitudinal brackets, supporting rails fixedly carried upon the lower portions of said life steamer and normally bearing upon said supporting rollers, said rollers being carried in a slanting plane so as to hold said life steamer in a tilted position, means for normally retaining the life steamer against accidental displacement, said means being adapted to be released upon the sinking of the ship, whereby the life steamer will ride over said supporting rollers and into the sea, and means carried upon said deck for guarding said supporting rollers and rails, thereby preventing a foreign object from engaging these elements and rendering the same inoperative.

4. In a device of the class described, the combination of a main ship having an upper deck, U-shaped brackets fixedly carried upon said upper deck, supporting rollers carried within said brackets and provided

with enlarged flanges upon a plurality of their side portions, said rollers being set in a slanting plane within said brackets, ears extending from the side portions of said brackets toward the central portions of said deck, guide rollers carried by said ears, a life steamer positioned above said deck, said life steamer provided with a plurality of supporting rails, said rails normally carried upon said supporting rollers and bearing against said flanges, and means for normally retaining said life steamer against accidental displacement, said life steamer being adapted to ride upon said supporting rollers whereby upon the releasing of said life steamer it may pass from the upper deck of said ship and rest upon the surface of the sea, said life steamer being adapted to engage said guide rollers whereby the life steamer will be positively prevented from accidentally moving over the side portions of the ship when the same is released.

In testimony whereof I hereunto affix my signature in presence of two witnesses.

ENOS THOMPSON.
